UNITED STATES PATENT OFFICE.

HENRY J. ORMSBY, OF EUREKA, KANSAS.

DESIGN FOR A TUG-FASTENER.

SPECIFICATION forming part of Design No. 35,434, dated December 10, 1901.

Application filed November 2, 1901. Serial No. 80,962. Term of patent 14 years.

To all whom it may concern.

Be it known that I, HENRY J. ORMSBY, a citizen of the United States, residing at Eureka, in the county of Greenwood and State of Kansas, have invented and produced a new and useful Design for a Tug-Fastener, of which the following is a full, clear, and exact description, reference being had to the accompanying drawings, in which—

Figure 1 is a perspective view of a fastener constructed in accordance with my invention. Fig. 2 is a top plan view. Fig. 3 is a side view. Fig. 4 is a sectional view on the line 4-4 of Fig. 3.

Referring specially to the drawings, A indicates the main or body portion, having

circular apertures A'. This body portion is curved, as shown at B, but is contracted and arched, as shown at C, the end being curved, as shown at D, and terminating in a gradual 20 rounding point E. Between the arched portion C and the end D is a rounded neck portion F.

Having thus fully described my invention, what I claim as new, and desire to secure by 25 Letters Patent, is—

The design for a tug-fastener, substantially as herein shown and described.

HENRY J. ORMSBY.
